UNITED STATES PATENT OFFICE.

ELEUTHERE PAUL DU PONT, OF MONTCHANIN, DELAWARE.

MACHINE FOR PACKING FUSES.

1,381,909.

Specification of Letters Patent. Patented June 21, 1921.

Application filed May 13, 1918. Serial No. 234,316.

To all whom it may concern:

Be it known that I, ELEUTHERE PAUL DU PONT, a citizen of the United States, residing at Montchanin, county of New Castle, 5 and State of Delaware, have invented a new and useful Improvement in Machines for Packing Fuses, of which the following is a full, clear, and exact description, reference being had to the accompanying drawings, 10 which form a part of this specification.

The manufacture of pellets of explosive material by molding the powder with gasolene under pressure while expelling a substantial part of the gasolene is known. My 15 invention has for its object to provide a machine to adapt this process to the manufacture of time fuses, wherein the powder is pressed into a straight tubular bore, the length of the bore or the composition of the powder 20 determining the time of burning. Specifically, the objects are to supply fractional parts of the entire quantity of powder constituting the fuse between the strokes of a continuously working ram; to press the 25 several charges with a uniform pressure whether before pressure the fuse container contains much or little powder; to cause the complete fuse to be held so firmly within the fuse container as to insure against its 30 falling out or becoming dislodged; to guard against the existence of any condition which might cause accidental explosion; and to enable filled fuse containers to be removed and to be replaced with fuse containers to 35 be filled without stopping the operation of the machines.

A preferred embodiment of the invention is shown in the accompanying drawings, wherein—

40 Figure 1 is an elevation of a part of a complete apparatus.

Fig. 2 is an end view of the same.

Fig. 3 is an enlarged view of the lower 45 part of one of the presses, the means for feeding powder to the fuse holder being omitted.

Fig. 4 is a vertical section on the line 4—4 of Fig. 3, with the said powder feeding means added.

50 Fig. 5 is a detail view of the valve for controlling the operation of the hydraulic actuating mechanism of the means for controlling the valve.

Fig. 6 is an elevation, partly in section, of 55 the fuse holder block.

Fig. 7 is a vertical section through the fuse holder block on line 7—7 of Fig. 6 and a fuse container held therein.

Fig. 8 is a detail view of the fuse container.

Fig. 9 is a section through one of the water pipes showing the check valve therein for regulating the flow of water in opposite directions therethrough.

Fig. 10 is an elevation, partly in section, 65 of the ram for packing the fuse.

The rifle grenade fuse, which is a name often applied to the brass container for the powder fuse proper, but which, for convenience of nomenclature, I shall herein-after call the fuse container, consists of a barrel *a* (see Figs. 7 and 8) having a powder fuse bore *b* extending longitudinally or axially therethrough and intersected by a hole *c* extending transversely through the 70 relatively thick base of the barrel. In charging the fuse container, a plug *d* is inserted within the cross-hole *c* and the charge of powder, which I shall hereinafter call the fuse, is pressed into the bore *b* from 75 the small diameter end of the fuse container down to the plug *d*, which acts as a stop and is afterward withdrawn.

To hold the fuse container in the machine, I provide a fuse holder block *e*, which 80 is a yoke-shaped casting having in its overhanging member a powder feed hole *f*, which also acts as a guide for the ram, and in its base a hole in which is inserted a cylindrical block *g*, which I call the fuse 85 container support. This support *g* is engaged by a turnable handle *h*, which works and rests against the cam surface of the base. This cam is so formed that it rises 90 comparatively steeply from its lowest level 95 *i* to its central part and thence has a very gradual rise to its high point *j*. The top of the movable support *g* is countersunk with a thirty degree taper to adapt it to receive the large diameter end of the fuse 100 container and hold it centrally.

When the handle is turned so as to engage the low part of the cam, there is a sufficient distance between the overhanging member of the block *e* and the support *g*, notwithstanding the countersink in the hole *f* and the countersink in the support *g*, to allow the fuse container to be inserted between them. By turning the handle *h* from the low part of the cam to the high part, the 105 110

support *g* is elevated at first rapidly and then slowly, locking the fuse container firmly into place.

Upon the top of the fuse holder block *e* is mounted a funnel *k* which communicates with the hole *f*. It will be understood that if powder, or a mixture of powder and gasolene, is placed in the funnel *k*, and if a ram *m* of sufficient length and with a sufficient stroke is operated to reciprocate into and out of the hole *f* and on its down stroke reach the bottom of the bore *b* of the fuse container or descend as far as is necessary to compress the powder that has already been charged into the container, a fractional part of the powder charge or fuse will enter the fuse container at each withdrawal of the ram and be compressed into the container at each downward movement of the ram.

When the complete charge is pressed into the container (means for indicating which is hereinafter described), the handle *h* is turned to the low point of the cam, the fuse container is removed, another fuse container is inserted, and the handle *h* is moved to the high point of the cam, and the operation of filling a fresh fuse container proceeds.

In case the hole *f* is rammed full, or partly full, of powder, which will occur if any excess over that required to fill the fuse container is fed into the hole *f*, the action of removing the fuse container will break off the powder train even with the end and the next stroke of the ram will push out the small cake and leave the hole *f* clear to start the next operation.

While, in the above description, I have spoken of the reciprocating movement of the ram, it will be understood that it is not material whether this movement is actual or merely relative. I prefer to stationarily secure the ram *m* to a block on the bed plate *n* and to reciprocate the block *e*. The block *e* is provided with side lugs *o* to which are secured the lower ends of two rods *p*, which, at their upper ends, are secured to a yoke *r*, which in turn is secured to the piston rod *s* of a piston working in a hydraulic cylinder *t*, which is secured to the bed plate *n*.

Water under regulated pressure is caused to pass into the lower end of the cylinder *t* and to discharge from the upper end, thereby moving the piston and the fuse holder block *e* up. Then water is caused to pass into the upper end of the cylinder and to discharge from the lower end, thereby moving the piston and the fuse holder-block down.

I provide a series of presses such as I have described (each comprising a fuse holder block, a ram, and a cylinder and piston for reciprocating the fuse holder block). Two pipes *u* and *v*, which may conveniently be termed headers, extend horizontally along the several hydraulic cylinders, each cylinder being connected top and bottom with the

respective headers by means of pipes *w* and *x*. The headers *u* and *v* extend (see Fig. 5) to a valve casing *y*, within which works a valve *z*, which is in every way similar to that used on a steam engine and need not, therefore, be described in detail. Communicating with the valve casing is a water supply pipe 10 and a water discharge pipe 11. As the valve moves back and forth it first connects one of the headers *u* or *v* with the supply pipe 10 and the other header with the discharge pipe 11, causing the pistons and the fuse holder blocks to move in one direction, and then reverses the connections, causing the pistons and the fuse holder blocks to move in the other direction, and so on.

The valve *z* is operated by means of a lever 12, which is pivoted between its ends to a bracket on the bed plate and is connected at its lower end to the stem of the valve. To operate the lever 12 automatically, there is provided a rotary cam disk 14 which engages a roller 13 on the lever. The cam is so designed that the valve *z* will be held in one operative position a much longer time than in the other operative position in the other. The purpose of this provision is to provide for the ram *m* of each press moving (relatively) downward comparatively slowly into the corresponding fuse container and withdrawing comparatively rapidly, as hereinafter particularly explained. I prefer that the relative durations of occupancy of the two positions shall be respectively three seconds and seven seconds. The cam shown is so shaped as to dictate approximately this action. The cam is a grooved cam and it will be observed that it widens out throughout a portion of that part of its circumference within which the roller travels during the up stroke of the pistons. This widened-out portion is of such a width that if the rotation of the cam be stopped while the roller is engaged with this portion of the cam, the lever 12 can be moved by hand to shift the valve. This provision is made for the purpose of adjusting the machinery.

While I have stated that the cam is so shaped as to cause the valve *z* to occupy one operative position a considerably longer time than the other operative position, it is evident that once the valve *z* shifts to make the connections required to dictate the positive stroke of the press, an unrestricted flow of water to the cylinder would cause the stroke of the press to proceed rapidly and complete its stroke long before the expiration of the time allotted to it, the press then remaining stationary until the reversal of the valve *z*. It is found that in pressing powder, when the ram makes a rapid stroke, air is likely to be imprisoned in the fuse container and the high compression of this

air raises its temperature sufficiently to effect the ignition of the powder. If, however, the stroke of the ram is made slow enough, there is sufficient leakage, both between the ram and the bore of the fuse container and at the lower end of the bore around the plug, to allow sufficient air to escape to prevent its reaching a pressure and temperature high enough to cause ignition. The most convenient way of insuring this slow movement is to throttle the flow of water to or from the cylinder. Obvious means for so throttling the flow are not available, inasmuch as provision must be made for allowing the water to flow more rapidly in the reverse movement of the press.

I accomplish the result desired by means of a check valve 16, which may be located in either pipes *w* or pipe *x* so long as it is arranged to open to allow free flow of water during that movement of the press which effects the withdrawal of the ram. I have shown it as located in the pipe *x*. An ordinary check valve placed in this position would open to allow this free flow in one direction, but would close and prevent the flow of water in the opposite direction, so that the press would not thereafter operate at all. On the other hand, if the check valve did not seat tightly, but leaked, then a slow reverse movement of the press would be possible, the piston moving only as fast as the rate of leakage of water through the check valve would permit. I take advantage of this fact by, in effect, providing a leaky check valve. Preferably, a groove 17 is filed in the valve, as indicated in Fig. 9. The dimensions of this groove are such that the water is allowed to "leak" through the valve, in the up-stroke of the pistons, at the rate required to cause this up-stroke to occupy the entire time which it is desired it should take. This slow movement has the additional advantage of giving adequate time for the gasoline to escape and thus permit the powder to be thoroughly pressed into place.

The mixed powder and gasoline is contained (see Fig. 4) within a feed main 18, from which extends a spout 19, the passage of the mixture from the main to the spout being controlled by a valve 20, which is operated by a hand lever 21. From the spout 19 the mixture drops into the funnel *k*.

To one of the rods *p* (see Fig. 3) connecting each fuse holder block *e* with its corresponding piston is secured a stop 22, in line of movement of which is a swinging lever or "indicator" 23, which rests against the pin 24 whenever the lower end of the ram *m* is not below the level of the top of the bore of the fuse container.

The operation of the machine may be briefly summarized as follows: The operator moves the handle *h* onto the low part of

the cam *i*, *j* and waits for the press to come to a standstill at the bottom of its down-stroke; that is, when the fuse holder block is at its lowest position and the ram has been withdrawn to its maximum extent. The fuse container *a*, into which the plug *d* has previously been placed, is properly positioned and is then locked in that position by turning the handle *h* to elevate the supporting block *g*. The hand lever 21 is operated to cause the mixture of powder and gasoline to flow from the main 18 through the spout 19 into the funnel *k*. Some of this mixture flows through the hole *f* into the bore *b* of the fuse container. The up-stroke of the press causes the ram *m* to press this powder firmly into the lower end of the bore of the fuse container. On this up-stroke of the press the pin 22 lifts the indicator 23 into the dotted line position shown in Fig. 85. The press now descends and an additional portion of the powder mixture descends into the bore of the fuse container. On the succeeding up-stroke of the press, the ram *m* presses the fresh charge against the previously pressed charge, but necessarily does not enter as far into the bore of the fuse container as on the first up-stroke of the press and hence the indicator is not lifted as high as the dotted line position 95 shown. The operation continues until the bore of the fuse container is packed full, after which the indicator 23 is not lifted from the pin 24. Hence the operator knows that it is time to remove the fuse container, which he does. He then inserts a new fuse container, refills the funnel *k* and the operation is repeated.

While I prefer to use a mixture of powder and gasoline, my invention is not restricted to handling of any particular mixture, the machine being adapted to the packing, in any fuse container, of explosive powder by itself or in other mixtures.

It is clear, from the foregoing description, that the machine may be operated continuously, and that while it is desirable, in order to secure the maximum output, to remove a filled fuse container and insert a new one as soon as a container is filled, any oversight or delay in this regard does not affect the successful operation of the machine. The pressure exerted upon the powder within the fuse container is always the same irrespective of the amount of powder in the container, and after the container is filled the fuse is of uniform density throughout its length. The fuse is pressed into its container so firmly that it cannot fall out or be accidentally dislodged. The operation, except for the supplying of powder and the removal and positioning of fuse containers, is entirely automatic, which gives not only the advantage of uniform output but also the advantage of rapid production, the latter 130

result not being modified by the limited manual operation necessary, which takes place while the automatic mechanism is in a transition position doing no useful work.

5 Having now fully described my invention, what I claim and desire to protect by Letters Patent is:

1. In a machine for packing time fuse powder in fuse containers, a holder comprising an abutment adapted to engage one end of the container, a support for the other end of the container movable toward and from the abutment, a turnable handle engaging the support, and a cam engaged by the handle and determining the distance of the support from the abutment.

10 2. In a machine for packing time fuse powder in fuse containers, a holder comprising an upper member against which one end of the fuse container is adapted to abut, a bottom member, a support movable up and down in the bottom member, a turnable handle engaging the support, and a cam engaged by the handle and adapted, as the handle is turned, to lift it or allow it to drop, thereby determining the level of the support.

15 3. In a machine for packing time fuse powder in fuse containers, the combination with a press comprising two members, one of said members being a holder for the container and the other a ram adapted to engage the bore of the container, of hydraulic mechanism for reciprocating one of said members; said hydraulic mechanism comprising a cylinder, a piston, pipes and a valve to control the direction of flow through the pipes; and means to reciprocate said valve and cause a flow through said pipes substantially slower in one direction than in the other.

20 4. In a machine for packing time fuse powder in fuse containers, the combination with a press comprising two members, one of said members being a holder for the container and the other a ram adapted to engage the bore of the container, of hydraulic mechanism for reciprocating one of said members; said hydraulic mechanism comprising a cylinder, a piston, pipes and a valve to control the direction of flow through the pipes; and means to throttle the flow of water in one direction so as to insure a relatively slow movement of said movable member during that movement thereof which effects the compression of the powder.

25 5. In a machine for packing time fuse powder in fuse containers, the combination with a press comprising two members, one of said members being a holder for the container and the other a ram adapted to engage the bore of the container, of hydraulic mechanism for reciprocating one of

30 said members; said hydraulic mechanism comprising a cylinder, a piston, pipes and a valve to control the direction of flow through the pipes, means to reciprocate said valve to hold it substantially longer in one operative position than in the other; and means to throttle the flow of water in one direction.

35 6. In a machine for packing time fuse powder in fuse containers, the combination with a press comprising two members, one of said members being a holder for the container and the other a ram adapted to engage the bore of the container, of hydraulic mechanism for reciprocating one of said members; said hydraulic mechanism comprising a cylinder, a piston, pipes and a valve to control the direction of flow through the pipes; a check valve in one of said pipes adapted to permit a free flow of water in one direction, and means permitting a leakage through the check valve while it is seated during the flow of the water in the opposite direction.

40 7. In a machine for packing time fuse powder in fuse containers, the combination with a press comprising two members, one of said members being a holder for the container and the other a ram adapted to engage the bore of the container, of hydraulic mechanism for reciprocating one of said members; said hydraulic mechanism comprising a cylinder, a piston, pipes and a valve to control the direction of flow through the pipes, and a check valve in one of said pipes, said valve having a cut-away portion permitting a restricted flow of water therethrough when it is seated.

45 8. In a machine for packing time fuse powder in fuse containers, the combination with a press comprising two members, one of said members being a holder for the container and the other a ram adapted to engage the bore of the container, of hydraulic mechanism for reciprocating one of said members; said hydraulic mechanism comprising a cylinder, a piston, pipes and a valve to control the direction of flow through the pipes, and a cam connected with said valve and adapted to impart thereto a differential speed movement.

50 9. In a machine for packing time fuse powder in fuse containers, the combination with a press comprising two members, one of said members being a holder for the container and the other a ram adapted to engage the bore of the container, of hydraulic mechanism for reciprocating one of said members; said hydraulic mechanism comprising a cylinder, a piston, pipes and a valve to control the direction of flow through the pipes, a rotatable cam, and an oscillating lever connected with the valve and operated by the cam, said cam being shaped to

swing said lever in one direction during substantially less than half of each revolution of the cam.

10. In a machine for packing time fuse powder in fuse containers, the combination with a press comprising two members, one of said members being a holder for the container and the other a ram adapted to engage the bore of the container of hydraulic mechanism for reciprocating one of said members; said hydraulic mechanism comprising a cylinder, a piston, pipes and a valve to control the direction of flow through the pipes, a rotatable disk provided with a grooved cam, and an oscillating lever connected with the valve and operated by the cam, said groove being substantially widened at one point to allow the lever to be moved independently.
15. In a machine for packing time fuse powder in fuse containers, the combination with a press comprising two members, one of said members being a holder for the container and the other a ram adapted to engage the bore of the container, of means to reciprocate one of said members and at every alternate stroke thereof compress the powder in the container, and an indicator operable to indicate the extent to which the bore of the container is filled.
20. 11. In a machine for packing time fuse powder in fuse containers, the combination with a press comprising two members, one of said members being a holder for the container and the other a ram adapted to engage the bore of the container, of means to reciprocate one of said members and at every alternate stroke thereof compress the powder in the container, and an indicator operable to indicate the extent to which the bore of the container is filled.
25. 12. In a machine for packing time fuse powder in fuse containers, the combination with a press comprising two members, one of said members being a holder for the container and the other a ram adapted to engage the bore of the container, of means to reciprocate one of said members and at every alternate stroke thereof compress the powder in the container, a movable indicator, and means moving with said reciprocable member and adapted, during the movement of the ram within the bore of the container, to move the indicator away from its normal position to an extent varying with the extent to which the ram enters said bore.
30. 13. In a machine for packing time fuse powder in fuse containers, the combination with a press comprising two members, one of said members being a holder for the container and the other a ram adapted to engage the bore of the container, of means to reciprocate one of said members, said mechanism comprising a cylinder, a piston therein, a fluid supply, a fluid discharge, pipes connected with opposite ends of the cylinder, a valve to connect said pipes respectively with the fluid supply and fluid discharge and to reverse said connections, and means in one of the pipes permitting an unrestricted flow of fluid in one direction and throttling its flow in the opposite direction.
35. 14. In a machine for packing time fuse powder in fuse containers, the combination with a press comprising two members, one of said members being a holder for the container and the other a ram adapted to engage the bore of the container, of means to reciprocate one of said members, an indicator attached to one of said members, and a stop secured to the other, said stop being so positioned that it will displace said indicator as long as the said ram engages the bore of the container.
40. 15. In a machine for packing time fuse powder in fuse containers, the combination with a press comprising two members, one of said members being a holder for the container and the other a ram adapted to engage the bore of the container, of means to reciprocate one of said members, a movable indicator and a stop therefor adjacent the press, and means secured to the reciprocated member adapted to move the indicator away from the stop a distance proportionate to that to which the ram enters the bore of the container.

In testimony of which invention, I have hereunto set my hand, at Wilmington, Delaware, on this 11th day of May, 1918.

ELEUTHERE PAUL DU PONT.
